C. E. BURROWS.

REVERSE MOTION,

APPLICATION FILED OCT. 8, 1920.

1,421,163.

Patented June 27, 1922.

UNITED STATES PATENT OFFICE.

CHARLES E. BURROWS, OF VESTAL, NEW YORK.

REVERSE MOTION.

1,421,163.

Specification of Letters Patent. Patented June 27, 1922.

Application filed October 8, 1920. Serial No. 415,534.

To all whom it may concern:

Be it known that I, CHARLES E. BURROWS, of Vestal, in the county of Broome, in the State of New York, have invented new and 5 useful Improvements in Reverse Motions, of which the following, taken in connection with the accompanying drawings, is a full, clear, and exact description.

This invention relates to a reverse motion 10 adapted to be used in various appliances for converting rotary into reciprocatory motion, and involves a right hand screw and a left hand screw secured coaxially end to end and driven from any available source of power, 15 in combination with a lever centrally pivoted upon a sliding support and having its opposite ends provided with segmental nuts, together with means for automatically effecting the rocking movement of the lever 20 in reverse directions to alternately engage the nuts with their respective screws for reciprocating the sliding support lengthwise of the screws, so that the reciprocatory movement may be utilized in the operation 25 of pumps, ratchets and other appliances requiring reciprocatory motion.

The main object is to increase the general working efficiency of devices of this character, and, at the same time, to reduce the 30 number of parts to a minimum and to arrange those parts in compact relation, whereby the entire device may be installed in a relatively small space and more nearly in direct connection with the parts to be 35 operated.

Another object is to enable certain parts of the device to be adjusted for varying the distance of travel of the reciprocatory elements.

40 Other objects and uses relating to specific parts of the device will be brought out in the following description.

In the drawings:

Figure 1 is a longitudinal vertical sectional view of a reverse motion mechanism embodying the various features of my invention.

Figure 2 is a horizontal sectional view taken in the plane of line 2—2, Fig. 1, showing one pair of guides and adjacent portion of the supporting frame, together with the means for adjusting and holding them in their adjusted position.

Figures 3 and 4 are transverse sectional views taken, respectively, in the plane of 55 lines 3—3 and 4—4, Fig. 1.

As illustrated, this device comprises a substantially rectangular main supporting frame —1— having lengthwise parallel side rails —2— and end walls —3— connecting 60 the same, said end walls being provided with bearings —4— for receiving the opposite ends of a rotary shaft —5— having a right hand thread —6— and a left hand thread —6'— secured coaxially end to end through 65 the medium of the shaft —5— and rotatable therewith.

One end of the shaft —5— extends through and beyond one of the end walls of the frame —1— and is provided with a pulley —7— adapted to be connected by a belt 70 to any available source of power, not shown, for rotating the shaft continuously.

The side rails —2— are each provided with a pair of lengthwise ribs —8— projecting inwardly from their inner faces in the same horizontal plane, preferably above the screw shaft —5—, the outer ends of each pair being spaced apart from the adjacent end walls —3— to form intervening passages —9—, while the inner ends of each pair are also spaced apart to form an intervening passage —10—, said passages serving to permit the pins of the reversing lever, presently described, to pass therethrough 85 from a position below to a position above the ribs —8—, and vice-versa, as will be herein-after more fully explained.

Each guide rib —8— is constructed in such manner that its effective length may be 90 varied at will, and, for this purpose, it is made of lengthwise sections or strips —11— of substantially the same form and size but reversed end for end with their major portions overlapping and slidably lengthwise of 95 and upon each other, one end of one section and the opposite end of the other section being provided with a lateral offset head —12— having a boss —13— projecting into a lengthwise slot —14— in the adjacent rail 100 —2— of the frame for lengthwise adjustment therein.

The end of each section —11— opposite the offset —12— is also provided with a lug —15— movable in a lengthwise slot —16— 105 in the companion section —11— for holding

said sections in parallelism and permitting their relative lengthwise adjustment along the adjacent supporting rail —2— for varying the effective length of the guide rib, and thereby varying the amount of movement of the reciprocating member presently described. The heads —12— of the rib sections —11— are provided with threaded studs —17— for receiving washers —18— and nuts —19— by which the sections may be clamped in their adjusted positions and released for adjustment when desired.

A cross-head —20— is slidable lengthwise of and upon suitable lengthwise ways —21— 15 on the opposite side rails —2— and preferably surrounds the shaft —5—, as shown more clearly in Fig. 3, leaving sufficient clearance for lengthwise movements of both the shaft and cross-head without friction 20 one with the other.

A lever —22— extends lengthwise of and directly over the screw shaft —5— and is centrally pivoted at —23— to the upper portion of the cross-head —20— for vertical 25 rocking movement, each end of said lever being provided with a segmental nut —24—, both of which are movable alternately into and out of engagement with their respective screws —6— and —6'— as the cross-head 30 —20— with the lever thereon is shifted longitudinally by the engagement of either nut with its corresponding screw.

Suitable pins —25— are secured to the opposite ends of the lever —22— just above 35 their respective nuts —24— and preferably equal distances from the pivot —23— for engagement with the lower and upper faces of the ribs —8—, as the head —20— with the lever —22— thereon is shifted longitudinally in reverse directions, and serve to hold one of the nuts in engagement with its corresponding screw and to similarly hold the other nut out of engagement with the other screw.

45 A plunger —26— is movable vertically in a hub —27— on the upper portion of the frame —1— directly over the adjacent ends of the screws —6— and —6'—, and also directly over the lever —22—, and is yielding- 50 ly held against the upper edge of said lever by means of a coil spring —28— within the hub —27—, and having one end bearing against the plunger and the other end against the upper wall of the hub, as shown 55 more clearly in Figs. 1 and 3, the lower end of said plunger being provided with a contact roller adapted to ride along and upon the upper edge of the lever —22— to reduce friction.

60 The combined length of the screws —6— and —6'— between the end walls —3— is somewhat greater than the length of the lever —22— and combined lengths of the 65 guide ribs —8—, which are adjusted to allow the pin —25— to release their engagement

with the ends of their corresponding ribs —8— under the action of the plunger —26— before either nut —24— reaches the outer end of its corresponding screw when the ribs —8— are adjusted for a maximum 70 amount of reciprocating movement of the cross-head —20—.

On the other hand, the sections —11— of the guide ribs —8— may be adjusted to shorten the effective lengths of their respective ribs —8— when it is desired to reduce the amount of reciprocating movement of the cross-head.

It is, of course, evident that the guide ribs —8— may be permanently secured in a fixed 80 position to their respective side rails when the reciprocating movement of the cross-head —20— is to remain the same, but, in either case, when the device is in action, the nut at one end will be released from the 85 corresponding outer end of the rib at the same time that the other nut is released from the inner end of the other rib, thereby allowing the plunger —26— to force the last named nut into engagement with its corresponding screw, and to release the other nut from engagement with the adjacent screw.

Operation.

95

Assuming that the screw shaft —5— is being rotated and that the left hand nut, Fig. 1, is in engagement with the screw —6—, in which position the opposite nut would be disengaged from the corresponding screw —6'—, then, as the lever —22— and its supporting cross-head —20— is shifted to the left, the left hand pin —25— will ride against the underside of the adjacent rib —8—, while the opposite pin will ride upon the upper face of the right hand rib, during which time, the plunger —26— will exert downward pressure upon the right hand end of the lever —22— so that as soon as the left hand pin —25— reaches the outer end of the left hand rib —8—, the right hand pin —25— will have reached the inner end of the right hand rib —8—, thus permitting the pressure exerted upon the right hand end of the lever —22— to rock said end downwardly, thereby forcing the right hand nut —24— into engagement with the corresponding screw, while the left hand nut will be moved out of engagement with the adjacent screw.

Under these conditions, the direction of movement of the lever —22— and its supporting cross-head —20— will be reversed with the left hand pin —25— riding upon the upper face of the adjacent rib —8— and the right hand pin against the lower face of the right hand rib until the right hand pin —25— reaches the outer end of its corresponding rib —8— and the left hand pin reaches the inner end of the adjacent rib, 130

whereupon, the lever —22— will be restored to its starting position ready for a return movement, this operation being repeated automatically as long as the shaft —5— 5 continues to rotate.

What I claim is:

1. The combination of a rotary screw, a nut movable into and out of engagement with the screw and actuated lengthwise thereof when engaged therewith, and means including a guide extending lengthwise of the screw for holding the nut in engagement with the screw during a predetermined movement of said nut along the screw and for releasing it from said engagement at the end of said movement.
- 10 2. The combination of a rotary screw, a nut movable into and out of engagement with the screw, and means for holding the nut in engagement with the screw during a predetermined movement thereof along the screw and for releasing it at the end of said movement, said means including a guide extending lengthwise of the screw and a 25 nut-supporting lever in sliding engagement with the guide.
3. The combination of a rotary screw, a nut movable into and out of engagement with the screw, and means for holding the 30 nut in engagement with the screw during a pre-determined movement thereof along the screw, and for releasing it at the end of

said movement, said means including a guide adjustable to vary the effective length thereof and to thereby vary the distance of movement of the nut along the screw before being released from engagement therewith.

4. The combination of a rotating screw, a reciprocatory member, a lever pivotally mounted on said member, a nut mounted on the lever and movable into and out of engagement with the screw as the lever is rocked in reverse directions, means for holding the lever rocked in one direction to engage the nut with the screw during a predetermined movement of the nut and lever by said screw and for releasing the nut and lever at the end of said movement, said means including a guide adjustable to vary its effective length and to thereby vary the 50 distance of travel of the lever and its supporting member along the screw, means for operating the released lever at the end of said movement to disengage the nut from the screw, and means for returning the released lever and its support in a direction opposite to that produced by the engagement of the nut with the screw.

In witness whereof I have hereunto set my hand this 25 day of September, 1920.

CHARLES E. BURROWS.

Witnesses:

EARL HAWKINS,
HOWARD MURDOCK.
